UNITED STATES PATENT OFFICE

AMANDA EDSEN WILSON, OF GLEN ELLYN, ILLINOIS

DOOR CONTROL MECHANISM

Application filed August 6, 1931. Serial No. 555,573.

The present invention contemplates a door-control mechanism, including a sliding latch normally holding a pair of hinged doors closed, and subsequently utilized to hold said doors open, and controlled in its movements by a single operating cable.

In carrying out the invention, the latch is initially actuated by an operating cable to release said doors, and incident to the opening movements thereof, the latch is shifted to its second active position to hold the doors open, the latch being subsequently actuated by the same cable to release said doors, which latter together with said latch are automatically returned to their normal position.

The invention aims to provide a mechanism of the above-mentioned character, which is simple in construction, and capable of being quickly and conveniently set up for use without requiring any alterations of the building structure, and one which is easy to operate and not very apt to become impaired.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a fragmentary sectional view of a building structure showing the normal position of the latch and its associated parts.

Figure 2 is a similar view, illustrating by dotted lines the doors of the structure opened, and the corresponding position of the latch.

Figure 3 is a fragmentary view partly in section showing the doors closed.

Figure 4 is an enlarged fragmentary view partly in section, showing how the doors are latched when opened.

Figure 5 is a perspective view of the latch. I have illustrated the invention in connection with the doors of a garage structure, but it is of course to be understood that it is applicable to any swingingly mounted door, and the general application of the invention is of course contemplated by the claims.

In the drawings, 10 indicates a building structure, preferably a garage, equipped with a pair of swingingly mounted doors indicated at 11.

The means for controlling the movements of these doors, forming the subject matter of the present invention preferably includes a horizontally disposed bar 12 of rectangular contour in cross section, and which bar is arranged within the building structure directly above the meeting edges of the doors. The forward end of the bar 12 is suitably connected with the adjacent wall of the building structure, while the opposite end of this bar is supported by a bracket 13 depending from an overhead support indicated generally at 14. Mounted to slide longitudinally on the bar 12 is a sleeve-like latch 15, clearly illustrated in Figure 5. This latch is of course of rectangular contour in cross section to accommodate itself to the bar 12, and projecting from the opposed longitudinal side of the latch are apertured lugs 16. These lugs receive the offset extremities 17 of a pair of links 18, the corresponding outer extremities of which are pivotally connected with the doors 11 as at 19 in any suitable manner. Obviously, by reason of this construction, the latch 15 is moved longitudinally of the bar 12 incident to the opening and closing movements of the doors.

The normal position of the latch 15 is clearly illustrated in Figures 1 and 2, in which position the doors 11 are closed. For holding the latch in its normal position, the latch is provided with a laterally projecting bolt 19, beveled toward one end and carried by one side of the latch as illustrated in Figure 5. Pivotally mounted on the bar 12 adjacent one end is a lever 20 having an offset extremity 21 forming a shoulder adapted to engage the bolt 19 as shown in Figure 1. The lever 20 is provided with a weight 22 which of course holds the lever in the path of movement of the bolt 19, so that when the latch is returned to its normal position, the adjacent end of the lever will pass beneath the beveled portion of the bolt, until the latter occupies the position illustrated in Figure 1, whereupon the lever will assume its normal position to engage the

bolt for the purpose stated. The lever 20 is also provided with an extension 23 having an eye through which one end of an operating cable 24 is passed and secured. This cable 24 is arranged parallel with the bar 12, and is guided through a suitable eye 25 secured to the adjacent wall of the building structure, with the free extremity of the cable depending therefrom so that it can be conveniently grasped to move the lever 20 upon its pivot and thereby effect a release of the latch 15, when it is desired to open the doors. Subsequent to the release of the latch 15 in the manner just stated, the doors 11 can be easily pushed to their open positions illustrated by dotted lines in Figure 2, and incident to the opening movements of the doors, the latch 15 is shifted from its normal position, to its second active position illustrated by dotted lines in Figure 2. In the position occupied by the latch, as illustrated by dotted lines in Figure 2, the latch is utilized to hold the doors 11 in their opened positions, and for which purpose, the latch is provided with a bolt 26 supported by the upper wall of the latch adjacent the forward end thereof. This bolt is also provided with a beveled surface 27.

Supported upon the front wall of the building structure immediately above the door opening is a bracket plate 28, upon which is pivotally mounted as at 29 a lever 30 which extends across the bar 12 and has its free end arranged behind a lug or keeper 31 carried by the bracket plate 28. This construction is clearly illustrated in Figure 3. This lever 30 is provided with a relatively broad lower portion as clearly illustrated in Figure 4, and the underside of this portion is recessed as at 32 to receive and accommodate the bolt 26 of the latch 15. By virtue of this construction, it is manifest that when the latch 15 is moved from its normal position to the position illustrated by dotted lines in Figure 2, incident to the opening of the doors 11, the bolt 26 will pass beneath the lever 30, elevating the latter, until the bolt 26 is arranged directly beneath the recess 32, whereupon the lever 30 will gravitate to its active position to engage the bolt 26. Consequently the latch 15 is held against movement, and the doors are held in their opened positions. As hereinabove stated, the operating cable 24 which is initially utilized to release the latch 15 from the lever 20, is subsequently used to release the latch from the lever 30, when it is desired to close the doors 11, and for this purpose the lever 30 is provided with an offset eye extension 33 through which the cable 24 passes. However, the cable is provided at an appropriate point in its length with an enlargement 34, preferably a ball as illustrated in Figure 4, and when the cable 24 is pulled upon, with the latch in the position illustrated in Figure 4, the enlargement or ball 34 will strike the ex-

tension 33 of the lever 30, thereby rocking this lever upon its pivot to effect a release of the latch 15. Subsequent to the release of the latch 15 from the lever 30, the doors 11 as well as the latch 15 are automatically returned to their normal positions. This may be accomplished in various ways, but I preferably employ a weight 35 suspended by a flexible element 36 trained over a guide pulley 37, and which element is connected to a projection 38 rising from the top of the latch 15.

In practice, the parts are normally in the position illustrated in Figure 1, and to open the doors 11 from inside the building structure, it is only necessary to pull upon the operating cable 24. When this cable is initially operated, the lever 20 is rocked upon its pivot to effect a release of the latch 15, so that the doors can be pushed open, incident to which movement of the doors, the latch 15 is shifted longitudinally on the bar 12 to the position illustrated by dotted lines in Figure 2. As the latch assumes this position it is engaged by the lever 30, and thus utilized to hold the doors open. In order to close the doors, it is only necessary to again operate the cable 24, whereupon the ball or enlargement 34 of the cable will operate the lever 30 to effect a release of the latch 15, whereupon the doors and latch will be automatically returned to their normal positions as above described.

While it is believed that from the foregoing description the nature and advantages of the invention will be readily apparent, I desire to have it understood that I do not limit myself to what is herein illustrated or described, and that such changes may be resorted to when desired as fall within the scope of what is claimed.

What I claim as new is:

1. A door locking device comprising in combination with a door, a bar having its front end fastened adjacent and above the door, a bracket supporting the rear end of the bar, a sleeve-like latch slidably disposed on the bar and having an integral laterally projecting lug, a link pivoted at one end to the door and at the opposite end to said lug, a beveled bolt integral with and projecting laterally from the rear end of said latch, a further beveled bolt integral with and projecting upwardly from the front end of said latch, a latch lever pivoted on a side of the bar near the rear end of the latter to automatically engage the laterally projecting bolt when the door is closed, a further latch lever pivoted above the front end of the bar to automatically engage the upwardly projecting bolt when the door is opened, and means to disengage the latch levers from said bolts.

2. The door locking device claimed in claim 1, in which the second-named latch lever is provided with an eye extension, and wherein the latch lever disengaging means consists of

10 a cable attached at one end to the first-named
latch lever and extending through said eye
extension of the second-named latch lever,
said cable having an enlargement arranged
5 to strike the eye extension of the second-
named latch lever when the cable is pulled.

15 In testimony whereof I affix my signature.

AMANDA EDSEN WILSON.
